UNITED STATES PATENT OFFICE.

FERDINAND BEAUMONT, OF NEW YORK, N. Y.

DESIGN FOR A CROUSTADE.

No. 37,588.

Specification for Design.

Patented Oct. 24, 1905.

Application filed July 1, 1905. Serial No. 268,003. Term of patent 14 years.

To all whom it may concern:

Be it known that I, FERDINAND BEAUMONT, a citizen of the United States, residing at New York, in the borough of Manhattan and State of New York, have invented a new, original, and ornamental Design for Croustades, of which the following is a specification, reference being had to the accompanying drawings, forming part thereof, in which—

Figure 1 is a plan view, and Fig. 2 is a side elevation, of a croustade, showing my design.

I claim—

The ornamental design for a croustade, as shown.

FERDINAND BEAUMONT.
